UNITED STATES PATENT OFFICE.

CHARLES R. DAELLENBACH, OF PARKGATE, PENNSYLVANIA, ASSIGNOR TO H. C. FRICKE, J. J. FLANNERY, AND G. E. TURNER, OF PITTSBURG, PENNSYLVANIA, AND JOSEPH M. FLANNERY, OF BRADDOCK, PENNSYLVANIA.

EXPLOSIVE-ENGINE.

SPECIFICATION forming part of Letters Patent No. 745,423, dated December 1, 1903.

Application filed September 29, 1902. Serial No. 125,342. (No model.)

To all whom it may concern:

Be it known that I, CHARLES R. DAELLENBACH, a citizen of the United States, residing at Parkgate, in the county of Lawrence and State of Pennsylvania, have invented new and useful Improvements in Explosive-Engines, of which the following is a specification.

My invention relates to explosive-engines, and has for one of its objects to provide a plural-cylinder engine in which the cylinders are directly connected without the interposition between them of working valves or other parts in such manner that after the engine is started the compression of the explosive mixture or fuel may be depended on to ignite the same.

Another object is to provide means for controlling the exhaust and regulating the power of the engine.

Other advantageous features of the invention will be fully understood from the following description and claims when taken in conjunction with the accompanying drawings, in which—

Figure 1 is a vertical section of a double-cylinder explosive-engine constituting the preferred embodiment of my invention; Fig. 2, a vertical transverse section taken in the plane indicated by the broken line 2 2 of Fig. 1; Fig. 3, a detail horizontal section taken in the plane of the broken line 3 3 of Fig. 1; Fig. 4, a detail section taken in the plane of the broken line 4 4 of Fig. 1 looking in the direction indicated by the arrow; Fig. 5, a view similar to Fig. 1 of a modification, and Fig. 6 a detail section illustrating a modification.

Similar letters of reference designate corresponding parts in Figs. 1 to 4 of the drawings, referring to which—

A B are the engine-cylinders, arranged side by side, with a wall *a* between them; C, a piston which divides the cylinder A into chambers D and E; F, a piston which divides the cylinder B into chambers G and H; I I, pitmen connecting the pistons C F with cranks J of a shaft K, journaled in the cylinders; M, a passage connecting the upper portions of

the chambers D G and having its end in the 50 latter disposed downwardly, so as to cause explosive mixture to take a downward course therein; P, a passage formed in the wall *a* and interposed between the chamber D of cylinder A and the chamber H of cylinder B, and 55 R, a passage formed, by preference, in the rear portion of the cylinder-wall for connecting the chambers D and E. This passage R contains, by preference, a suitable regulating-valve S and has a port T, designed to be connected with a gas or gasoline source of supply or with a suitable carbureter, as preferred.

The end of the passage P which communicates with the chamber H of cylinder B is controlled by the piston F, while the other 65 end of said passage P—*i. e.*, that connected with the chamber D of cylinder A—is controlled by the piston C, as are also the ends of the passage R which communicate with the chambers D and E of cylinder A. The 70 pistons C F are preferably hollow, as shown, and the former is provided with a port U, Fig. 2, designed to register with the lower end of the passage R, and the latter with a port V, Fig. 1, designed to register with the 75 lower end of the passage P. The pistons are also provided with deflectors W, disposed as shown in order to cause compressed air to take the courses indicated by arrows precedent to passing from the interior of the pistons 80 into the passages P R.

The chambers E H of the cylinders A B are provided with ports X, preferably controlled by non-return valves, for the entry of air, and the chamber G of cylinder B is connected 85 with a chamber Z, which has a port *a'* open to the air and contains a relief or exhaust valve *b*. The latter connection is preferably effected by a port Y, interposed between the upper portion of the chamber G and the portion of 90 chamber Z above the valve *b*, and a port or ports Y', Figs. 1 and 3, connected to the chamber Z below the valve *b* and to the chamber G at such a point as to be uncovered by the piston F as the same approaches the completion of the outward stroke thereof. The passage Y' is preferable, because it permits 95 free egress of the products of combustion at

the end of the outward stroke of the pistons and renders it unnecessary to make the port Y and chamber Z unduly large.

The valve b is interposed between the port 5 Y and the exhaust-port a' and is normally held to its seat c by a spring d, which surrounds the stem e of the valve and is interposed between the casing and an enlargement on said stem, as shown. The valve-stem carries 10 an antifriction-roller g and is adapted to be operated by a cam h on shaft K through the medium of mechanism hereinafter described. The cam h is preferably shaped as shown, Fig. 4, and hence it follows that the 15 valve b will be held in its open position incident to a considerable portion of each revolution of the shaft K for a purpose presently described.

The chamber G of cylinder B is preferably 20 arranged close to the chamber D of cylinder A, as shown, in order that after the engine is started the explosive mixture may be ignited by the compression thereof. The engine when 25 small may be started by the operator turning the balance-wheel (not shown) with which the shaft K is ordinarily equipped; but when the engine is of large horse-power the initial explosion or explosions of the explosive mixture are effected and the engine started by a 30 hot tube, electric spark, or other means, which I have deemed it unnecessary to illustrate, located, by preference, in the chamber D, or by any other means. After the engine 35 is started the compression of the explosive mixture is by preference depended on to ignite the same.

With the engine in operation it will be seen that when the pistons C F are nearing the end 40 of their outward stroke the valve b is closed, the end of the passage P contiguous to the chamber D of cylinder A is partly uncovered, as is also the passage Y', and the port V in 45 piston F is registered or partially registered with the end of said passage P contiguous to the chamber H of cylinder B. The registration of the port p and passage P permits the 50 compressed air in the chamber H to pass through the passage P into the chamber D of cylinder A and results in the products of combustion of the previous explosion being forced through the port or passage M into the chamber G of cylinder B and from thence through the passage Y' and chamber Z to the open air. When the pistons reach the end 55 of their outward stroke, the lower end of the passage P is closed by the piston F, as shown in Fig. 1, and the port U of piston C is registered with the end of the passage R contiguous to the chamber E. In consequence of this 60 the explosive mixture contained in the chamber E of cylinder A passes through the port or passage R into the chamber D. At this time the pistons C F move inwardly, the inner end of the passage Y' is closed, and the valve b starts to open and remains open until the 65 pistons have traveled about two-thirds of their inward stroke, when said valve is closed,

and the compression of the explosive mixture commences. At this time the compression rapidly increases until the crank-pins reach 70 the dead-center, when the explosive mixture will be ignited, the pistons forced outwardly, and the operation described repeated. Incident to the subsequent inward movement of the pistons the piston C will operate to draw 75 a charge of air into the chamber E and also a quantity of gas or gasolene, which will become mixed with the air. The lower end of the passage R is preferably shaped as shown in order to enable it to hold any surplus gaso- 80 lene that may enter through the port T.

The operation described in the foregoing is the operation of the construction shown in Figs. 1 to 5 of the drawings. When a branch passage P' is provided between the lower end 85 of the passage P and the chamber E and a port V' is provided in the piston C, as shown in Fig. 6, the operation will be the same as that described, except that when the ports V V' are registered with the branches at the 90 lower end of the passage P and also when the pistons are above said branches the chambers E H will be in communication with each other. In virtue of this it will be observed that but one port X, controlled by a non-return valve, is necessary to supply both chambers E H with air. I prefer, however, when the branch P' and port R' are employed to employ both ports X and use some means to temporarily close the one connected to the 95 chamber E. Then in the event of the non-return valve controlling the other port X becoming choked or disabled the port X connected to the chamber E may be opened to 100 said chamber. I also desire it understood 105 that I may when desired provide a valve or cut-off (not shown) in the branch P' for controlling communication between the passage P and the chamber E.

By reason of the employment of the two 110 chambers D G, connected as described, it will be observed that subsequent to each explosion the gases are enabled to expand to atmospheric pressure, or, in other words, are enabled to expand and act against the pistons until their energy is exhausted, with the result that the full power of the explosion is utilized and the power of the engine materially increased in proportion to the amount of fuel consumed. It will also be observed that 115 the reduction of the pressure of the gases to that of the atmosphere eliminates all noise incident to the exhaust and renders the employment of mufflers unnecessary. Moreover, it will be seen that the two pistons offer a 120 great amount of surface to the expanding gases at the moment of the explosion, with the result that a powerful movement is transmitted to the crank-shaft at the time when the pressure is maximum and the value of the 125 expansion the greatest.

I desire it distinctly understood that the cylinders A B may be of the same size as shown in Fig. 1, or the cylinder B may be

larger than the cylinder A, in about the proportion shown in Fig. 5, as desired. The latter construction possesses all of the advantages of the construction shown in Fig. 1, and is further advantageous, since subsequent to each explosion the combustion-space is rapidly increased, which contributes to quick and complete combustion and the production of the maximum power from the fuel consumed without increasing the speed of the moving parts to the danger-point.

Incident to the operation of the engine it will be observed that precedent to each explosion the expansion-chambers are cleared of all spent gases or products of combustion and then filled with a pure explosive mixture, and subsequent to each explosion the gases are expanded to a great extent. The thorough clearing of the expansion-chambers of spent gases or products of combustion, as above described, is materially advantageous, because it precludes back or premature explosions and assures the expansion-chambers containing pure explosive mixture alone at the time the explosion takes place, which contributes materially to the efficiency of the engine.

While the cylinders A B are connected without the interposition between them of valves or other working parts, such as are liable to be deteriorated by the products of combustion, it will be seen that the connection is effected in such manner that the chamber D is charged with explosive mixture, and the mixture is prevented from entering the chamber G until the piston F in said chamber G has completely discharged its volume of air and products of combustion. This contributes to the ability of the pistons to permit rapid expansion of the gases of the subsequent explosion, which is desirable, as before stated.

My improved engine is further advantageous in that it has no openings through which explosive mixture may escape to the atmosphere and reduce the power of the engine; in that the inlet-ports and exhaust-ports of the chambers D G are in such relative positions that the entering charge of explosive mixture cannot escape with the products of combustion; in that the ports of the pistons are so disposed that incident to the opening of the ports hot air is exhausted from the pistons, thereby preventing overheating of the moving parts and effecting the discharge of oil from the lower or crank chambers to the explosion-chamber, and in that the compression does not take place until the cranks approach the dead-center, which reduces the back pressure of the engine to the minimum.

It is desirable, as when the engine is to be used to propel vehicles, to provide means through the medium of which the attendant may temporarily increase the power of the engine. The means I prefer to employ for this purpose comprises a hand-lever *f*, fulcrumed on the bearing surrounding the crank-shaft

K and adapted to be adjustably fixed to said bearing by a set-screw *f'* or adjustably secured in any other approved manner, a link *i*, pivotally connected to lever *f* and having a curved portion *j*, provided with a slot *k*, and also having an antifriction-roller *l* on said curved portion, a lever *m*, fulcrumed on a stationary support, as the casing of the engine, and arranged to engage the antifriction-roller *g* of the valve-stem *e*, said lever *m* having an antifriction-roller *n* arranged to be engaged by cam *h* and mounted on a bolt *p*, which is free to work or move in slot *k* of link *i*. This mechanism is calculated to change the time of closing the exhaust or relief valve *b* without changing the time of opening said valve, which is advantageous, because when the valve is closed early the compression of the explosive mixture is increased, which effects a temporary increase in power, and also because when the closing of the exhaust-valve is delayed there is less compression, which facilitates starting of the engine.

When the lever *f* is moved in the direction of the arrow in Fig. 4, the antifriction-roller *l* on the link *i* is moved forwardly with respect to the antifriction-roller *n*, or, in other words, the distance between the roller *l* and the roller *n* is increased. When the distance between the said rollers *l* and *n* is thus increased, the exhaust-valve is held open for a longer period than would otherwise be the case, owing to the fact that the valve cannot close until the cam *h*, which engages the roller *l* after the roller *n*, passes out of engagement with said roller *l*. When the lever *f* is moved in the opposite direction to that indicated by arrow and the distance between the roller *l* and the roller *n* is diminished, the cam *h* will pass more quickly out of engagement with said roller *l*, and consequently the exhaust-valve will be held open for a shorter period, which accomplishes the increase of power before mentioned. The time at which the exhaust-valve is opened is not changed, because the position of roller *n* with respect to cam *h* is not changed, and therefore as soon as the cam engages said roller *n* the lever *m*, acting against roller *g*, raises the valve.

Having described my invention, what I claim, and desire to secure by Letters Patent, is—

1. An explosive-engine comprising two cylinders, and pistons therein; the cylinders having expansion-chambers between their heads and the pistons, and the pistons being connected to move synchronously, a passage connecting the two chambers, a passage connected with one chamber for supplying the same with fluid-pressure, a passage connected with the said chamber for supplying the same with fuel under pressure, a relief-valve connected to the other chamber, mechanism operated by the engine for operating said relief-valve, and means for varying the time of closing said valve.

2. The combination in an explosive-engine,

- of two cylinders, and pistons therein; the cylinders being divided by the pistons into expansion-chambers and compression-chambers, the expansion-chambers being in communication, and one expansion-chamber being connected with one compression-chamber by a passage, and with the other compression-chamber by an independent passage; said passages being controlled by the pistons, a connection between the pistons whereby they are caused to move together, an exhaust-port communicating with one expansion-chamber, means for controlling the exhaust-port, an air-inlet port, and a fuel-supply port.
3. The combination in an explosive-engine, of two cylinders, and pistons therein; the cylinders being divided by the pistons into expansion-chambers and compression-chambers, the expansion-chambers being in communication, and one expansion-chamber being connected with the compression-chambers by passages controlled by the pistons, a connection between the pistons whereby they are caused to move together, an exhaust-port communicating with one expansion-chamber, and controlled by the piston therein, a relief-valve connected to the said chamber, mechanism operated by the engine for operating said relief-valve, an air-inlet port, and a fuel-supply port.
4. The combination in an explosive-engine, of two cylinders, and pistons therein, the cylinders being divided by the pistons into expansion-chambers and compression-chambers, and the pistons being connected together to move synchronously, a passage intermediate of the compression-chamber and expansion-chamber of one cylinder, and having its ends arranged to be overrun by the piston therein, a passage intermediate of the expansion-chamber of said cylinder and the compression-chamber of the other cylinder, and having its ends arranged to be overrun by the pistons of the two cylinders, an exhaust-passage connected with one of the expansion-chambers, and means for controlling the exhaust.
5. The combination in an explosive-engine, of two cylinders, and pistons therein, the cylinders being divided by the pistons into expansion-chambers and compression-chambers, and the pistons having ports, a shaft journaled in the cylinders and having cranks within the compression-chambers connected with the pistons, air-inlet ports opening into the compression-chambers, a passage intermediate of the compression-chamber and expansion-chamber of one cylinder, and connected with a source of gas or gasoline supply, passages intermediate of the expansion-chamber of said cylinder, and the compression and expansion chambers, respectively, of the other cylinder, an exhaust-port communicating with the expansion-chamber of the latter cylinder, and means for controlling the exhaust.
6. The combination in an explosive-engine,

- of two cylinders, and pistons therein, the cylinders being divided by the pistons into expansion-chambers and compression-chambers, and the pistons being hollow and having ports and deflectors disposed below the same, a shaft journaled in the cylinders and having cranks within the compression-chambers, connected to the pistons, air-inlet ports opening into the compression-chambers, a passage intermediate of the compression-chamber and expansion-chamber of one cylinder, and connected with a source of gas or gasoline supply, passages intermediate of the expansion-chamber of said cylinder and the compression and expansion chambers, respectively, of the other cylinder, a valve-chamber communicating with the expansion-chamber of the latter cylinder, and having an exhaust-port, a valve in the valve-chamber provided with a stem, means for returning the valve to and normally holding it against its seat, and means for opening the valve and holding it open for a portion of each revolution of the shaft.
7. In an explosive-engine, the combination with two cylinders provided with a passage connecting their clearance-spaces one of said cylinders being provided with a fuel-inlet port and the other provided with an exhaust-port, two auxiliary compression-chambers, connections between the cylinder provided with the inlet-port and one of said compression-chambers, a separate connection between the said cylinder and the other compression-chamber, a relief-valve connected to the other cylinder, pistons in said cylinders, connected to move synchronously, and adapted to control said ports and connections, means for admitting air to said compression-chambers and mechanism operated by the engine for operating said relief-valve, substantially as described.
8. In an explosive-engine, the combination with two cylinders provided with a passage connecting their clearance-spaces, one of said cylinders being provided with a fuel-inlet port and the other provided with an exhaust-port, two auxiliary compression-chambers, connections between the cylinder provided with the inlet-port and one of said compression-chambers, a separate connection between the said cylinder provided with the inlet-port and one of said compression-chambers, a separate connection between the said cylinder and the other compression-chamber, a relief-valve connected to the other cylinder-pistons in said cylinders, connected to move synchronously, and adapted to control said ports and connections, means for admitting air to said compression-chambers, mechanism operated by the engine for operating the said relief-valve, and adjustable devices for varying the time of closing of said relief-valve, substantially as described.

9. In an explosive-engine, the combination with two cylinders provided with a passage connecting their clearance-spaces, one of said

cylinders being provided with a fuel-inlet port and the other provided with an exhaust-port, two auxiliary compression-chambers, connections between the cylinder provided 5 with the inlet-port and one of said compression-chambers, a separate connection between the said cylinder and the other compression-chamber, a relief-valve connected to the other cylinder-pistons in said cylinders, connected 10 to move synchronously, and adapted to control said ports and connections, means for admitting air to said compression-chambers and mechanism for operating said relief-valve including a cam operated by the engine, a lever interposed between the cam and said valve and means for adjusting said lever to 15 vary the time of closing of said valve, substantially as described.

10. In an explosive-engine, the combination 20 with two cylinders provided with a passage connecting their clearance-spaces, one of said cylinders being provided with a fuel-inlet port and the other provided with an exhaust-port, two auxiliary compression-chambers 25 connections between the cylinder provided with the inlet-port and one of said compression-chambers, a separate connection between the said cylinder and the other compression-chamber, a relief-valve connected to the other 30 cylinder, pistons in said cylinders, connected to move synchronously, and adapted, to control said ports and connections, means for admitting air to said compression-chambers and mechanism for operating said relief- 35 valve, including a shaft operated by the engine, a cam on said shaft, an adjustable arm, and a lever pivoted to said arm and adapted to engage a part connected with said valve, substantially as described.

40. 11. The combination in an explosive-engine, of two cylinders, and pistons therein; the cylinders being divided by the pistons into expansion-chambers and compression-chambers, the expansion-chambers being arranged close 45 together and separated by a wall, and being also in communication, and one expansion-chamber being connected with one compression-chamber by a passage, and with the other compression-chamber by an independent passage; said passages being controlled by the 50 pistons; and one of said passages being formed in the wall between the expansion-chambers, a connection between the pistons whereby they are caused to move together, an exhaust- 55 port communicating with one expansion-chamber, means for controlling the exhaust-port, an air-inlet port, and a fuel-supply port.

12. The combination in an explosive-engine, 60 of two cylinders and pistons therein; the cylinders being divided by the pistons into expansion-chambers and compression-chambers, the expansion-chambers being in communica-

tion, and one expansion-chamber being connected with one compression-chamber by a passage, and with the other compression-chamber by an independent passage; said passages being controlled by the piston, an exhaust-port communicating with the inner portion of the other expansion-chamber, means for controlling said exhaust-port, an exhaust-port communicating with the outer portion of said expansion-chamber, and controlled by the piston therein, a connection between the pistons, an air-inlet port and a fuel-supply port. 75

13. The combination in an explosive-engine, of two cylinders, and pistons therein, one of the cylinders being divided by its piston into an expansion-chamber and a compression-chamber, and the other having an expansion-chamber between its piston and head, an exhaust communicating with the inner portion of the latter expansion-chamber, means for controlling the exhaust, an exhaust-port communicating with the outer portion of said chamber and controlled by the piston therein, an air-inlet port, a passage intermediate of the compression and expansion chambers of the first-named cylinder having its ends arranged to be overrun and controlled by the piston therein, a fuel-supply port communicating with said intermediate passage, a passage intermediate of the expansion-chambers of the two cylinders, and a connection between the two pistons whereby they are 95 caused to move together.

14. The combination in an explosive-engine of two cylinders, and pistons therein; the cylinders being divided by the pistons into expansion-chambers and compression-chambers, the expansion-chambers being arranged close together and separated by a wall, and being also in communication, and one expansion-chamber being connected with one compression-chamber by a passage, and with the other 105 compression-chamber by an independent passage; said passage being controlled by the pistons; and one of said passages being formed in the wall between the expansion-chambers, an exhaust-port communicating with the inner portion of the other expansion-chamber, means for controlling said exhaust-port, an exhaust-port communicating with the outer portion of said expansion-chamber, and controlled by the piston therein, a connection between the pistons, an air-inlet port, and a fuel-supply port. 110 115

In testimony whereof I have hereunto set my hand in presence of two subscribing witnesses.
